O. C. BILLMAN

PENCIL

Filed July 28, 1919

Obed B. Billman

UNITED STATES PATENT OFFICE.

OBED C. BILLMAN, OF CLEVELAND, OHIO, ASSIGNOR OF ONE-HALF TO HARVEY H. TROXEL, OF WOOSTER, OHIO.

PENCIL.

Application filed July 28, 1919. Serial No. 313,791.

To all whom it may concern:

Be it known that I, OBED C. BILLMAN, a citizen of the United States, residing at Cleveland, in the county of Cuyahoga and State of Ohio, have invented certain new and useful Improvements in Pencils, of which the following is a specification.

My invention relates to improvements in pencils, and more particularly to that class or type in which the lead or marking material is projected or fed out of the pencil body at will and to the extent desired by manually operable means.

A further object is to provide a pencil of this class in which the lead may not only be projected, but may be retracted, as desired, by the relative rotation of the pencil parts.

The present improvements relate more particularly to improved means for storing a supply of lead within the pencil body, together with improved means for storing and projecting and retracting a suitable eraser.

A still further object is the provision of improved means whereby the eraser may not only be retracted and protected within the pencil body when not in use, but may be readily projected for use, when desired, and which will at the same time be ornamental in appearance.

With the above mentioned and other ends in view, the invention consists in the novel construction, arrangement and combination of parts, hereinafter described, illustrated in some of its embodiments in the accompanying drawings, and particularly pointed out in the appended claims.

Referring to the drawings, forming a part of this specification, Figure 1, is a central longitudinal sectional view of a propeller pencil constructed in accordance with this invention.

Fig. 2, is a longitudinal central sectional view of a pencil showing a modified form of the finger piece or cap embodying the improved means for retracting and projecting an eraser.

Fig. 3, is a view of a further modification of the finger piece or cap in which the eraser is manually brought into and out of position for use, instead of automatically, as shown in Fig. 2.

Fig. 4, is a cross sectional view of the form shown in Fig. 2, taken on line 4—4 of Fig. 2.

Fig. 5, is a perspective view of the lead or marker holder, detached from the slotted tubular propeller member or stem.

Fig. 6, is a fragmentary perspective view of the slotted propeller tube or stem, detached.

Fig. 7, is an enlarged fragmentary view of the top of the rotary propeller member and movable eraser and eraser carrying member and guide and guide stop members.

Similar numerals of reference designate like parts throughout all the figures of the drawings.

The improved pencil comprises a tubular main body portion 1, terminating in a pointed or tapered portion 1^a, the latter being provided at its point with an opening 1^b, through which opening 1^b, the split or feed end of the slotted propeller stem carrying the marker holder, hereinafter referred to, is adapted to project or retract, the lead being adapted to be projected and retracted through such split feed end of the propeller stem as will be hereinafter explained.

The tubular body 1, is preferably provided at its head or top portion with an annular outwardly extending rib or beading 1^c, against which the rotary finger piece or cap 2, is adapted to abut, or in the forms shown in Figs. 2 and 3, is adapted to engage or interlock, as will hereinafter be explained.

As a means of projecting or retracting the lead 3, with the forward and rearward rotary movements of the finger piece or cap 2, the interior of the lower portion of the tubular body 1, is preferably provided with a threaded portion 4, the latter being preferably in the form of a wire helix secured within the tubular body 1, and as a means of positively securing the lead or marker 3, so that the same will be projected and retracted, a marker holder 5, is provided, said marker or lead holder 5, being longitudinally movable in a longitudinally slotted tubular propeller member or stem portion 6, said slotted member or stem 6, being preferably connected to a second or enlarged tubular propeller member 7, and the latter being connected to the finger piece

- or rotary cap 2, in any suitable and convenient manner, as for example,—as hereinafter described. The slotted member or stem 6, is secured to the second tubular member 7, in 5 any suitable and convenient manner, as for example by means of a bottom piece or coupling member 7^a, the latter forming, in the present instance, the bottom of the lead receptacle 7^b, formed by the tubular member 7. 10 The connecting piece or coupling member 7^a, is secured to the lower end of the lead receptacle member 7, so as to be carried with the latter, as hereinafter described, and, if desired, may be threaded thereto, as shown. 15 As a means of causing the lead or marker holder 5, to be moved longitudinally with the rotary movements of the stem 6, and the second tubular member 7, as said propeller members 6 and 7, are rotated by the finger piece or cap 2, the lead or marker holder 5, is provided with a projection 5^a, extending through a slot 6^a, of the stem 6, and projecting between the convolutions of the helix or threaded portion 4, said projection being 20 preferably provided with a recess 5^b, to receive or straddle one of the convolutions of the helix and thus follow the same. 25 The lower end of the lead or marker holder 5, is provided with longitudinally extending spring tongues 5^c, adapted to firmly and securely engage the lead or marker 3, to positively retract the latter when the marker holder is retracted, and as a means of positively preventing any relative movement between the lead 3, and the marker holder when pressure is applied to the pencil the marker holder is provided with an inwardly extending projection or abutment 5^d, adapted to engage the top of the lead. 30 The upper end of the tubular member or receptacle forming the propeller portion 7, is provided with an eraser 8, and which in the form shown in Fig. 1, closes the lead receptacle, and affords access to the latter 35 when the cap 2, is removed. 40 In the forms shown in Figs. 1 and 3, the interior of the neck portion of the cap or finger piece 2, is provided with threads threaded upon a similarly threaded exterior portion of the top of the tubular member 7, while in the form shown in Fig. 2, the cap is indirectly connected thereto through the movable eraser and the mechanism for automatically projecting and retracting the 45 eraser to be hereinafter described. 50 As a means of detachably connecting the rotary or propeller members 6 and 7, within the tubular body to prevent longitudinal movement of the same while being rotated by the finger piece, and at the same time retaining the same so that it will operate after the cap has been removed, the rib or beading 1^c, in the form shown in Fig. 1, is 55 split and provided with an interior groove 1^d, adapted to fit over and interlock with

an exterior rib or beading 7^c, on the exterior of the part 7. In this way when the cap 2, is removed the parts 6 and 7, will still be retained in operative position for the operation of the pencil by turning the threaded 70 projecting portion of the propeller member 7 in the usual manner.

In the forms shown in Figs. 2 and 3, the cap or finger piece 2, is provided with an exterior rib 2^a, adapted to fit over and interlock with the exterior of the beading 1^c, of the pencil body to removably retain the propeller members 6 and 7, therein as against ordinary longitudinal removing movement and at the same time permit rotatable movement thereon. The beading 2^a, is adapted to interlock with a snap action, and, if desired, may be provided with a series of slits 2^b, forming spring tongues, as indicated in Figs. 2 and 3. In the forms shown in Figs. 2, 85 and 3, the finger piece or cap 2, is provided with a central opening 2^c, to removably receive and contain an eraser 8, and an eraser carrying member 8^a.

In the form shown in Fig. 3, the eraser 8, and eraser carrying member or cup 8^a, are adapted to be inserted or removed manually and to be held in their respective positions by means of a central supporting and clamping member 7^d, said supporting 95 member 7^d, having a central opening to receive the eraser 8, when the latter is reversed and protected, and may also be provided with an enlarged or shoulder portion 7^e, to support the edge of the eraser carrying or cup member 8^a, as indicated.

In the forms shown in Figs. 2 and 4, the finger piece or cap 2, has no direct connection with the tubular propeller members 6 and 7, the top of the tubular propeller member 7, being loosely arranged within the neck portion of the finger piece or cap and extending upwardly and being provided with a guide in the form of a slot 7^f, within which a projection or guide member 8^b, in the present instance, in the specific form of a screw, is adapted to travel.

Should it be desired to remove the cap or finger piece 2, from the propeller member 7, as shown in Fig. 2, of the drawings, the cap or finger piece 2, may be first elevated whereby the split beading 2^a, will be spread apart and detached from the annular outwardly extending rim or beading 1^c, of the pencil body 1, after which the cap 2, will be turned rearwardly to unthread or detach the threaded portions or spirally arranged grooves 2^f, at the bottom edges from the projection or guide member 8^b, of the eraser carrying member 8^a, whereupon the cap 2, may be lifted off of the top of the propeller member 7, and eraser 8. Should it then be desired to take out the eraser carrying member 8^a, and eraser 8, and gain 120 access to the lead carrying receptacle 7^b, the 125

eraser carrying member 8^a, may be removed by first detaching the screw or projection member 8^b, from the guide slot 7^t, as clearly shown in Fig. 7, of the drawings.

5 As a means of causing the eraser carrying member 8^a, and the eraser 8, to be projected and retracted through the opening 2^c, of the cap with the initial lead projecting and retracting movements of the 10 cap or finger piece 2, the interior of the latter is provided with spirally arranged grooves 2^t, adapted to receive the projection 8^b, so that when the eraser 8, and its carrying member 8^a, are in their retracted 15 position, as shown in Fig. 2, and the thumb or finger piece 2, is moved to the right, the initial movement will project the eraser upwardly to the dotted line position, until the upper terminal portion of the slot 7^t, 20 is engaged by the projection, whereupon the propeller members 7 and 6, will be rotated to the right to project the lead. After finishing writing with the pencil the movement of the finger piece or cap in 25 an opposite or reverse direction will cause the movement or retraction of the eraser toward its original or fully retracted and projected position, and when the lower terminal portion of the guide or slot 7^t, is engaged by the projection 8^b, the propeller 30 parts 6 and 7, will be moved in an opposite direction and retract the lead. It will thus be seen that the eraser will always be projected and retracted just prior to the 35 initial projection and retraction of the lead or marker.

The mechanism for holding and guiding the lead and for projecting the latter from or retracting the same within the pencil body, shown and described, but not claimed herein, is made the subject of a divisional application filed May 26th, 1923, Serial No. 641,553.

From the foregoing description, taken 45 in connection with the accompanying drawings, the operation and advantages of my invention will be readily understood.

Having thus described some of the embodiments of my invention, what I claim 50 and desire to secure by Letters Patent, is,—

1. In a propeller pencil, a tubular pencil body provided at its top with an annular beading, a tubular propeller member rotatable in said pencil body, an eraser in said 55 propeller member, a finger cap protecting said eraser and detachably connected to said propeller member, and means for detachably and rotatably securing said cap and propeller member to said annular beading of said pencil body.

2. In a propeller pencil, in combination 60 with a propeller member provided with a guide at one end, a relatively longitudinally movable eraser support carried on said end of said propeller and provided with a pro-

jection in engagement with said guide, a propeller actuating cap having a threaded portion engaging and moving said projection when rotated whereby said eraser support is projected or retracted by said cap prior to the initial forward and rearward rotary movements of said propeller member by said propeller actuating cap, and means for detachably and rotatably connecting said cap and propeller member and for 70 limiting the rotary movements of said cap.

3. In a propeller pencil, a tubular pencil body, a tubular propeller member therein and projecting therefrom and provided at its top with a lead receptacle, an eraser 80 removably mounted in said tubular propeller member above said lead receptacle, a cap member detachably secured to the projecting end of said propeller member and protecting said eraser, and means for removably retaining said propeller and cap members in rotatable connection with said pencil body.

4. In a propeller pencil, a tubular pencil body provided with an annular outwardly 90 extending beading, a tubular propeller member rotatable in and projecting above said pencil body, an eraser in said propeller member, a finger cap member protecting said eraser and detachably connected to and adapted to operate said propeller member, and means on one of said members for 95 rotatively securing said cap and propeller member to said annular beading of said pencil body.

5. In a propeller pencil, in combination, a propeller member provided with a guide, an eraser movably mounted on said propeller member and provided with a projection in engagement with said guide, a 105 detachable propeller actuating cap having a threaded portion engaging and moving said projection and eraser when rotated whereby said eraser is projected or retracted by said cap prior to the initial rotary movement of said propeller member by said propeller actuating cap.

6. In a propeller pencil, a pencil body, a propeller member removably and rotatably mounted in said pencil body, an eraser 115 detachably mounted in said propeller member, and a finger piece detachably mounted on said propeller member and said pencil body, said finger piece being adapted to insert and remove said propeller member and being provided with a central cavity to receive said eraser.

7. In a propeller pencil, a tubular pencil body provided with an annular outwardly 120 extending beading, a tubular propeller member therein and provided with a lead receptacle, an eraser removably mounted in said propeller member forming a closure for said lead receptacle, a cap member detachably secured to said propeller member and pro- 125

tecting said eraser, and means on one of said members for longitudinally retaining said propeller and cap members in rotative connection with said outwardly extending pencil body beading.

8. In a propeller pencil, a pencil body, a propeller member removably and rotatably mounted therein, an eraser and eraser carrying member detachably mounted in said propeller member, said eraser carrying member having a lateral projection extending through and having a limited longitudinal movement in said propeller member, and a finger piece detachably mounted on said propeller member and said pencil body and provided with an internal thread engaging said lateral projection and initially moving said eraser carrying member longitudinally and having a central opening receiving said eraser when projected therefrom by the operative engagement therewith of said finger piece.

9. In a propeller pencil, a pencil body, a propeller member provided at its top with an opening and removably and rotatably mounted in said pencil body, an eraser detachably mounted in said top opening of said propeller member, a finger cap on said propeller member, and means for securing the latter in said pencil body, said finger cap being adapted to insert and remove said propeller member in said pencil body and being provided with a central eraser receiving recess above said eraser.

10. In a propeller pencil, in combination with a pencil body and a rotary propeller member having one end projecting therefrom and provided with a longitudinal guide-way, an eraser and eraser carrying member mounted in said projecting end of said propeller member and provided with a guide stop member slidable in said guide-way, a finger cap provided with spiral grooves surrounding and engaging said guide stop member and having a limited rotary movement relatively thereof, and means for detachably connecting said finger cap and propeller member in relative rotatable relation to said pencil body, the construction and arrangement of the parts being such as to cause said eraser and eraser carrying member to be initially projected or retracted by the forward or rearward rotation of said finger cap and prior to the rotation of said propeller member by the latter.

11. In a propeller pencil, in combination with a pencil body and a propeller member removable therein and provided with a guide portion projecting therefrom, a relatively longitudinally movable eraser support carried within the projecting guide portion of said propeller member and provided with a projection in non-rotatable slidable engagement with said guide portion, a propeller actuating finger piece engaging and moving

said projection of said eraser support when rotated whereby said eraser is projected or retracted by said finger piece prior to the initial forward or rearward rotary movement of said propeller member by said propeller actuating finger piece, and means for detachably and rotatably connecting said finger piece and propeller member in normal assembled relation to said pencil body.

12. In a propeller pencil, in combination, a pencil body, a rotary propeller therein and projecting from one end of said pencil body, said projecting end being provided with a longitudinal guide-way, a finger piece detachably connected to said projecting end of said rotary propeller and provided with spiral grooves in slidable engagement with said guide member, said grooves terminating in terminal stops to limit the relative rotary movements of said finger piece and whereby said eraser carrying member is longitudinally moved prior to the initial rotary movement of said propeller member by said finger piece and said eraser carrying member is projected and retracted with the initial projecting and retracting movements of the finger piece, and means for detachably and rotatably connecting said finger piece and rotary propeller in normal assembled relation to said pencil body.

13. In a propeller pencil, a tubular pencil body provided at its top with an annular beading, a tubular propeller member in said pencil body projecting above said beading and provided with a lead receptacle, an eraser, an eraser carrying member on said propeller member forming a closure for the lead receptacle, a finger cap member detachably mounted on said propeller member and protecting said eraser, and a companion beading on one of said members detachably interlocking with said pencil body beading for longitudinally retaining said propeller and cap member in rotatable assembled relation to said pencil body.

14. In a propeller pencil, a tubular pencil body provided at its top with an annular outwardly extending beading, a tubular lead receptacle forming propeller member in said pencil body and projecting above said beading, an eraser, an eraser carrying member in said propeller member forming a closure for the lead receptacle, a finger cap member threaded on said propeller member and protecting said eraser, and a companion beading on one of said members detachably interlocking with said pencil body beading for longitudinally retaining said propeller and cap member in assembled relation to said pencil body.

15. In a propeller pencil, the combination with a pencil body and a removable propeller member provided at its top with a longitudinal guide way; of an eraser carrying member detachably mounted in said guide-

way, and a cap piece rotatably and detachably mounted on said propeller member and pencil body, said cap piece protecting said eraser carrying member and being provided with a feed screw in engagement with said eraser carrying member whereby the latter is projected or retracted upon the initial feeding or retracting movements of said finger piece prior to the initial movements of said rotary propeller member.

16. In a propeller pencil, a tubular pencil body provided with an annular beading, a tubular propeller member removably and rotatably mounted therein and provided with a lead receptacle, an eraser and eraser carrying member detachably mounted in said propeller member, and a finger cap detachably connected to said propeller member and provided with a split beading rotatably interlocking with said beading of said pencil body, said finger cap being provided with an internal thread engaging and initially moving said eraser carrying member and having a central opening receiving said eraser when projected by the operative engagement therewith of said finger piece.

17. In a propeller pencil, the combination with a pencil body and a rotary propeller member therein and provided at its top with a projecting portion having a longitudinal guide slot, and an eraser and eraser carrying member in said projecting portion mounted on and longitudinally movable with respect to said rotary propeller member and provided with a guide stop member resting in and controlled by said guide slot; of a finger piece mounted on said projecting portion of said propeller member and provided with internal spiral grooves in engagement with said guide stop member whereby said eraser and eraser carrying members are projected or retracted upon the initial feed or return movements of said finger piece and prior to the like movements of said rotary propeller member, and means for detachably and rotatably connecting said rotary propeller member and finger piece to said pencil body.

18. In a propeller pencil, in combination with a rotary tubular propeller member provided at one end with a longitudinal guide way and a lead receptacle, an eraser and eraser carrying member mounted to close said lead receptacle of said propeller member and provided with a projection slideable in and projecting from said guide way, and a finger cap covering said eraser and provided with spiral grooves surrounding and engaging said projection whereby said eraser and eraser carrying member are projected or retracted by the rotation of said finger cap.

19. In a propeller pencil, the combination with a pencil body and a rotary propeller member therein provided with a longitudinal guide way projecting from one end of said pencil body, and an eraser and eraser carrying member movably mounted in one end of said propeller member and provided with a guide in said guide way; of a finger piece detachably connected to said pencil body and covering said eraser and eraser carrying member and provided with an eraser receiving opening and having spiral grooves in engagement with said guide whereby said eraser and eraser carrying members are projected and retracted prior to the initial movements of said propeller member by said finger piece and said eraser is carried upwardly above and below the opening of said finger piece with the projecting and retracting movements of the latter.

20. In a propeller pencil, a pencil body, a rotary propeller member therein having an opening in its top and provided with a longitudinal guide slot, an eraser carrying member slideable in said rotary propeller member and provided with a guide stop member extending in and controlled by said guide slot, a finger cap member detachably connected to said pencil body and provided with an eraser receiving opening and an internal threaded feed portion, said cap when connected being rotatable on said pencil body and surrounding said propeller member and eraser carrying member and said threaded feed portion being in engagement with said guide stop member to initially move the latter to the ends of said guide slot whereby said eraser carrying member is projected or retracted prior to the initial movements of said propeller member by said finger cap, said eraser carrying member being provided with an eraser movable upwardly above and below the opening in said finger cap member with the initial movements of the latter.

21. In a propeller pencil, a tubular pencil body, a tubular propeller member therein and projecting from one end thereof, an eraser removably mounted in said projecting end of said tubular propeller member, a cap member covering the projecting end of said propeller member and protecting said eraser, and means for removably and rotatably retaining said propeller and cap members in assembled connection with said pencil body and for permitting said propeller member to be removed from the latter by the detachment of said cap member.

In testimony whereof I have affixed my signature.

OBED C. BILLMAN.
